UNITED STATES PATENT OFFICE.

GERHARDT G. OLSON, DECEASED, LATE OF CUSHING, OKLAHOMA, BY NANNA MERDELL
OLSON, ADMINISTRATRIX, OF CUSHING, OKLAHOMA.

OUTLET-VALVE AND CAP FOR TANK-CARS.

1,290,302.

Specification of Letters Patent.

Patented Jan. 7, 1919.

Application filed December 1, 1917. Serial No. 204,932.

To all whom it may concern:

Be it known that GERHARDT G. OLSON, deceased, late a citizen of the United States, residing at Cushing, in the county of Payne 5 and State of Oklahoma, did invent new and useful Improvements in Outlet-Valves and Caps for Tank-Cars, of which the following is a specification.

This invention relates to improvements in 10 outlet valves and caps for tank cars.

In carrying out the present invention, it is my purpose to provide an outlet valve and cap for tank cars whereby the valve will be held securely to its seat by the cap on the 15 lower end of the outlet casting so as to prevent any of the liquid from passing the valve and entering the outlet casting, and wherein the cap may be sealed to the casting so that the authorities will be advised 20 when the outlet valve casting is tampered with by unauthorized persons.

It is also my purpose to provide an outlet valve and cap for tank cars which will embrace the desired features of simplicity, efficiency and durability and which will be constructed in such manner that the same 25 may be readily opened and closed.

With the above and other objects in view, the invention consists in the construction, 30 combination and arrangement of parts hereinafter set forth in and falling within the scope of the claims.

In the accompanying drawing;

Fig. 1 is an enlarged fragmentary vertical sectional view through a tank car 35 equipped with a valve and cap constructed in accordance with the present invention.

Fig. 2 is a similar view through the outlet casting and associated parts.

Fig. 3 is a vertical sectional view showing 40 a modified form of cap.

Fig. 4 is a plan view of the dome.

Referring now to the drawing in detail, 1 designates a portion of a tank car having 45 an outlet opening 2 formed in the bottom thereof and a dome 3 formed on the upper portion thereof in line with the outlet opening 2. The edge of the outlet opening 2 is formed to provide a valve seat 3' and engaging the seat 3' is a valve disk 4. Connected 50 to the valve disk 4 and projecting upwardly therefrom and terminating within the dome 3 is a valve stem 5. Pivotaly connected to the inner wall of the dome 3 is one end of

a lever 6 and the upper end of the stem 5 55 is pivotally connected to the lever 6 at the center thereof and the other end of the lever is movable over a rack 7 that acts to hold the valve in adjusted position. By means of the lever 6, the valve 4 may be engaged 60 with and disengaged from the seat 3' and in order to hold the lever and the valve in adjusted position the lever may be engaged with the rack. 5' is a guide for the rod 5.

Secured to the bottom of the car coaxial 65 with the outlet opening 2 is an outlet casting 8 depending from the bottom of the tank car and having the lower end thereof exteriorly screwthreaded as at 9. Secured to the under side of the valve disk 4 in axial 70 alignment with the stem 5 and depending into the outlet casting 8 is a rod 10 having the lower end formed with an exteriorly threaded head 11 formed, at its upper end, with a shoulder 13. 14 designates a cap having 75 the inner surface of the side wall thereof threaded to engage the threads 9 on the lower ends of the outlet casting and formed in the end wall of the cap 14 at the center thereof is an outlet opening 15. On the inner side of the bottom wall of the cap is an upstanding boss 16 interiorly threaded to engage the threads on the head 11, and connected to the lower side of the end wall of the cap coaxial with the opening 15 therein 80 85 is a connecting nipple 17 exteriorly threaded to receive a cut off valve.

The side wall of the cap 14 and the casting 8 are formed with companion eyes 18 90 adapted to receive seals, while the lower wall of the cap 14 is formed with eyes 19 designed to connect the seal to the valve on the nipple 17.

In practice, the valve 4 is engaged with the seat 3' under the action of the stem 5 and the lever 6 and the cap 14 threaded onto the lower end of the outlet casting 8. As the cap is threaded onto the casting the boss 16 engages the head 11, thereby acting to pull upon the valve disk 4 through the medium 95 of the head and the rod 10. After the head has been threaded onto the outlet casting and the valve on the nipple 17 closed, the seals may be passed through the eyes 18 and secured to the valve on the nipple 17 and to 100 the eyes 19.

As will be seen in Fig. 4 the lever 6 is placed to one side of the opening in the dome

so as to be out of the way of a workman passing through said opening. 7 indicates a cover for said opening.

In the modified form of the invention, I 5 have shown the lower end wall of the cap 14 as formed with a depending boss 20 at the center thereof to accommodate a wrench and in this form of the invention, the opening 15, the nipple 17 and the cut off valve 10 are dispensed with, and the head 11 on the lower end of the rod 10 is also eliminated and the boss 16 threaded onto the lower end of the rod.

While I have herein shown and described 15 certain preferred forms of the invention by way of illustration, I wish it to be understood that I do not limit or confine myself to the precise details of construction herein described and delineated, as modification 20 and variation may be made within the scope of the claims and without departing from the spirit of the invention.

I claim:

1. The combination with a tank car having 25 an opening in the bottom thereof, a valve closing said opening, an outlet casting secured to the bottom of the car and arranged concentrically of the outlet opening, a valve rod connected with said valve and

projecting into the casting, a screw threaded 30 head on the end of said rod, a valve on the upper end of said head and a cap having screw threaded engagement with the end of the casting and provided with a screw 35 threaded projection engaging with the screw threaded head to hold the valve on its seat.

2. The combination with a tank car having an opening in the bottom thereof, a valve closing said opening, an outlet casting secured to the bottom of the car and 40 arranged concentrically of the outlet opening, a valve rod connected with said valve and projecting into the casting, a screw threaded head on the end of said rod, a valve on the upper end of said head, a cap 45 having screw threaded engagement with the end of the casting and an interiorly threaded boss in said cap with which the screw threaded head engages, said boss having a valve seat on its upper end to receive the 50 valve on the head and an outlet nipple carried by the cap and communicating with said boss.

In testimony whereof I affix my signature.

NANNA MERDELL OLSON.

Administratrix of Gerhardt G. Olson, deceased.
